UNITED STATES PATENT OFFICE.

WILLIAM HORACE AUNKST, OF MILTON, PENNSYLVANIA.

PNEUMATIC PUMP.

1,072,806.

Specification of Letters Patent. Patented Sept. 9, 1913.

Application filed February 14, 1913. Serial No. 748,429.

To all whom it may concern:

Be it known that I, WILLIAM H. AUNKST, a citizen of the United States, residing at Milton, in the county of Northumberland and State of Pennsylvania, have invented a new and useful Pneumatic Pump, of which the following is a specification.

The present invention appertains to pneumatic pumps or water elevators, and aims 10 to provide a novel and improved apparatus of this character.

One of the objects of the present invention is to provide an apparatus of the character indicated which may be lowered into 15 an Artesian well, a mine shaft, or the like, in order that water or other liquids therein may be elevated or hoisted by pneumatic pressure in an efficient and novel manner.

Another object of the present invention is to provide a device of the nature indicated 20 which shall embody a pair of superimposed compartments into which the water may flow alternately, the pump being operable by pneumatic pressure in order that the 25 water may be elevated alternately from the respective compartments to the surface or to any desired point.

A still further object of the present invention is to provide a novel means for permitting the air to escape from the respective 30 compartments, after the water has been forced therefrom, in order that fresh water may flow thereinto, so that a continuous or non-intermittent action of the pump may 35 ensue.

Another object of the present invention is to provide a pump of the character indicated which shall be of relatively small cross 40 sectional area so as to enter an Artesian well or circumscribed passage without detracting from the utility of the device, the device being capable of being constructed of various lengths according to the depth of the well or the like.

45 With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed can be made within the scope of what 50 is claimed without departing from the spirit of the invention.

The invention has been illustrated in its preferred embodiment in the accompanying drawing, wherein similar reference characters have been employed to denote corresponding parts, and wherein:

Figure 1 is a longitudinal central section of the apparatus, parts being broken away. Fig. 2 is a top or upper end view of the device. Fig. 3 is a fragmental detail in 65 section. Fig. 4 is a sectional detail of the valve structure for one of the compartments, which is operable to permit the air under pressure to enter the compartment, so as to force the water therefrom, and to then permit the air to be discharged from the compartment after the water has been forced therefrom. Fig. 5 is a cross section of the details illustrated in Fig. 4.

In carrying out the invention, reference 75 being had to the accompanying drawing, there are provided a pair of superimposed compartments or chambers 6 and 6', each of which may be of any desired length and cross section. The lower end or bottom of 80 the upper compartment is spaced sufficiently above the upper end or top of the compartment 6' and is provided with one or more inlets 7 closed normally by outwardly seating valves 8, while the lower end or 85 bottom of the compartment 6' is similarly provided with one or more inlets 7' normally closed by outwardly seating check valves 8'.

A cage or reticulated guard 9 is secured 90 between the adjoining ends of the compartments so as to permit of the influx of water, and in order to exclude the ingress of foreign or extraneous matter, and a similar cage or guard 9' is secured to the lower end 95 of the compartment 6'.

An air chamber or compartment 10 is mounted on the upper end of the compartment 6, the same being preferably in the form of a hood secured at its edges to the 100 compartment 6. The chamber 10 is provided with an inlet 11 to which is attached the supply or feed pipe for the compressed air or fluid. The supply of compressed air may come from any suitable source, as 105 will be evident.

The eduction or discharge pipe or conduit for the water has been designated by the numeral 12, the same extending interiorly of the compartments 6 and 6' along one side 110 thereof, and extending upwardly through the chamber 10 to the atmosphere or to any

desired point where the water is to be discharged. The conduit 12 terminates at its lower end adjoining the lower end of the compartment 6', and is provided adjoining the respective lower ends of the compartments 6 and 6', with the inlets 13 and 13' normally closed by the outwardly seating check valves 14 and 14'.

The upper end of the compartment 6 is provided with a pair of sleeves 15 and 15', which provide passages through the upper end of the compartment 6, and which are provided at their upper ends with the valve seats 16 and 16', respectively, on which are 15 seatable the respective valves 17 and 17'. The valves 17 and 17' are connected by a lever or walking beam 18 in order that the valves will move in opposite directions or in order that the valves will seat alternately. 20 The lever 18 is provided with an upstanding arm 19 to which is pivoted a plunger 20 working through a support or bracket 21 mounted within the chamber 10. The lever 18 is also fulcrumed or pivoted to the support or bracket 21, in order that the joint between the arm 19 and the plunger 20 may swing to either side of the axis of the device as the respective valves are seated. A coiled wire spring 22 is mounted on the plunger 20 and seats between the lower end of the plunger and the support 21, so as to yieldingly hold the arm 19 to one side or the other. Thus, it will be noted that the arm 19 and the plunger 20, when swung into alignment, will compress the spring 22, and when the lever 18 is swung in one direction or the other, the spring 22 will serve to seat the respective valves 17 or 17'.

The respective valves 17 and 17' are provided with the depending spiders 23 and 23' slidable in the respective sleeves 15 and 15', and to the respective spiders there are attached the depending actuating rods 24 and 24'. The lower end of the rod or link 24 is pivoted to a lever 25 fulcrumed within the compartment 6, while the rod or link 24' extends through the lower end of the compartment 6 and into the compartment 6', and is pivoted to a lever 25' fulcrumed 50 within the compartment 6'. The respective levers 25 and 25' have the links 26 and 26' hung therefrom, and to the lower ends of the respective links 26 and 26' are attached the floats or buoyant members 27 and 27'.

55 A pipe or tubular member 28 is passed through the lower end of the compartment 6 and is attached at its lower end to the upper end of the compartment 6', and at its upper end is attached to the lower end of the sleeve 15', so that the rod or link 24' may pass through the adjoining ends of the compartments 6 and 6' without the necessity of stuffing boxes or the like. It will thus be noted that the pipe 28 and the sleeve 15' 65 provide a passage from the air chamber 10

into the lower compartment 6', while the sleeve 15 provides a passage from the air chamber into the upper compartment.

The eduction or discharge pipe for the air has been designated by the numeral 29, the same passing through the hood or air compartment 10 and having a pair of branches 30 leading to the respective sleeves 15 and 15'. The branches 30 pass through the respective sleeves and have their extremities downturned or depending, as denoted by the numeral 31, Fig. 4. The extremities of the branches 30 are formed into valve seats 32, which face downwardly.

A valve 33 is carried within each of the spiders 23 and 23', and has a depending stem 34 passing slidably through the center hub of the spider. The stem 34 is provided with a nut or stop 35 on its lower end adapted to normally seat against the spider so as to limit the upward movement of the valve 33, and a coiled wire compression spring 36 is mounted on the stem 34 between the valve 33 and the spider so as to yieldingly support the valve 33. Each of the respective valves 33 is adapted to seat upwardly against the seat 32 when the respective valve 17 and 17' is raised, and when the respective valve 17 or 17' is seated, the corresponding valve 33 is lowered or unseated.

In the operation of the device, it being understood that the compartments 6 and 6' have been lowered into an Artesian well, mine shaft or the like, so that the water or other liquid may flow into the respective cages 9 and 9', the water may flow into the respective compartments 6 and 6' through the check-valved inlets. Taking the parts as depicted in Fig. 1, the compressed air or fluid is adapted to pass from the air chamber 10 down through the sleeve 15' and pipe 28 into the compartment 6', so that any water accumulated within the compartment 6' will be forced upwardly through the inlet 13' into and up the eduction conduit 12 to the surface or atmosphere. It will be noted that when the air flows or is forced into the compartment 6', the check valves 8' will be seated so as to prevent the water from being discharged through the inlets 7'. It will be noted that when the valve 17' is raised, the float or buoyant member 27' will be raised, and the respective valve 33 will be seated so as to prevent the egress of air through the pipe 29, and after the water has been forced from the compartment 6', the float 27' will be lowered or will gravitate so as to tend to seat the valve 17'. In the meantime, the valve 17 will be seated, and the valve 33 complementing the valve 17 will be unseated so as to open the respective branch 30 of the discharge pipe 29 and as a consequence, the water may flow through the inlets 7 into the compartment 6, the superincumbent air

being discharged through the pipe 29 to the atmosphere. It will also be noted that as the compartment 6 fills with water, the float 27 will be raised, and due to the combined or aggregate movements of the two floats, the lever 18 will be swung, clock-wise as seen in Fig. 1, so as to unseat the valve 17 and in order to seat the valve 17', the respective valves 33 being seated and unseated correspondingly. Thus, it will be observed that the floats 27 and 27' coöperate in a novel manner, the buoyant tendency of one float coöperating with the gravitating tendency of the other to swing the lever 18 and its arm 19 beyond dead center so as to reverse the positions of the valves 17 and 17'.

After the above operation has ensued, that is, after the compartment 6 has been filled or partially filled with water, and after the compartment 6' has been emptied, so as to unseat the valve 17 and seat the valve 17' the reverse operation will take place, the air now being forced through the sleeve 15 into the compartment 6 so as to force the water through the inlet 13 into and up the eduction conduit 12, the check valve 14' closing the inlet 13' leading to the compartment 6'. In the meantime the water will flow through the inlets 7' into the compartment 6', the air passing off through the pipe 28, the sleeve 15' and discharge pipe 29 to the atmosphere.

In the manner above described, it will be observed that each of the compartments is intermittently filled with water, and then emptied or discharged, the water being raised through the eduction conduit, and the action in the two compartments being alternate, to produce a practically continuous or steady flow of water through the eduction conduit 12. The operation of the device is entirely automatic, and it is to be observed, that the entire apparatus is devoid of stuffing boxes, or the like, which are objectionable, especially in a pump of the present character.

Having thus described the invention what is claimed as new is:—

50 1. A device of the character described including upper and lower compartments having check-valved inlets, an eduction conduit having check-valved inlets communicating with the respective compartments, an air chamber above the upper compartment, the upper compartment having a pair of openings leading to the air chamber, a pipe connected to one of the openings and passing through the upper compartment to the lower one, valves for closing the respective openings, and float controlled means within the respective compartments connected to the respective valves for alternately seating them, the float controlled means within the lower compartment being

connected to the respective valve through the aforesaid pipe.

2. A device of the character described including upper and lower compartments having check-valved inlets, an eduction conduit having check-valved inlets communicating with the respective compartments, an air chamber, an air passage extending from the lower compartment through the upper one to the air chamber, an air passage leading from the upper compartment to the air chamber, valves for the respective passages, float controlled means in the respective compartments and connected to the respective valves through the respective passages for alternately seating the valves, air outlet passages terminating within the respective aforesaid passages, and supplemental valves carried by the aforesaid valves for opening and closing the respective last mentioned passages as the respective aforesaid valves are seated and unseated. 70 75 80 85

3. A device of the character described including a pair of compartments having check-valved inlets, an eduction conduit having check-valved inlets communicating with the respective compartments, an air chamber, air passages leading from the air chamber to the respective compartments, valves for the respective passages, float controlled means within the respective compartments operably connected with the respective valves through the passages for alternately seating the valves, air outlet passages terminating within the respective aforesaid passages, and supplemental valves movable with the respective aforesaid valves to open and close the respective last mentioned passages as the respective aforesaid valves are seated and unseated. 90 95 100 105

4. A device of the character described including upper and lower compartments having check-valved inlets, an eduction conduit having check-valved inlets communicating with the respective compartments, an air chamber mounted on the upper compartment, the upper compartment having a pair of sleeves communicating with the air chamber, a pipe connected to one sleeve and passing through the upper compartment to the lower one, valves seatable on the respective sleeves and having spiders working therein, float controlled means within the respective compartments operatively connected to the respective spiders for alternately seating the valves, the float controlled means within the lower compartment being connected to the respective spider through the said pipe, air outlet passages terminating within the said sleeves, 110 115 120 125 and supplemental valves carried by the spiders, to open and close the respective passages as the respective aforesaid valves are seated and unseated.

5. A device of the character described in- 130

cluding a water compartment having a check-valved inlet, an eduction conduit having a check-valved inlet communicating with the said compartment, an air chamber, 5 an air passage leading from the compartment to the air chamber, a valve for the said passage, float controlled means in the said compartment and connected to the said valve through the said passage for seating the valve, an air outlet passage terminating 10 within the aforesaid passage, and a supplemental valve carried by the aforesaid valve for opening and closing the last mentioned passage as the aforesaid valve is seated and unseated.

6. A device of the character described including a water compartment having a check-valved inlet, an eduction conduit having a check-valved inlet communicating

with the said compartment, an air chamber, 20 the said compartment having a sleeve communicating with the said air chamber, a valve seatable on the sleeve and having a spider working therein, float controlled means within the compartment operatively connected to the spider for seating the valve, an air outlet passage terminating within 25 the sleeve, and a supplemental valve carried by the spider, to open and close the last mentioned passage as the aforesaid valve is seated and unseated.

In testimony that I claim the foregoing as my own, I have hereto affixed my signature in the presence of two witnesses.
